X-RAY TUBE

Albert Bouwers, Eindhoven, Netherlands, assignor to N. V. Philips' Gloeilampenfabrieken, Eindhoven, Netherlands, a limited liability company of the Netherlands

Application March 25, 1927, Serial No. 178,457
In the Netherlands April 19, 1926

21 Claims. (Cl. 250—34)

This invention relates to X-ray tubes which are so constructed that any danger during the operation of the tubes is avoided, this application forming in part a continuation of my copending 5 application, Serial No. 5,108, filed January 27, 1925. The inconvenience of the X-rays emerging not only in the direction in which they are desirable, but in any direction, has been obviated before by constructing a tube as indicated in the 10 application for patent Serial No. 673,166, November 6, 1923. When operating tubes of this construction the parts which are under high voltage constitute a source of danger. This danger is also obviated by the construction according 15 to the invention.

It is known to arrange the high tension transformer and the X-ray tube (which is entirely of glass) within a vessel which is entirely filled with oil. The high tension cables are also entirely 20 immersed in the oil.

As a rule X-ray installation constructed in this manner substantially produce no danger to the patient and to the operator. The disadvantage of such installations is, however, that their 25 volume and weight are great when compared with the X-ray energy radiated. One object of the invention is to provide an improved construction of an X-ray tube which is entirely protected both with respect to undesired X-rays and to the danger arising from high tensions. Another object 30 of the invention is to provide an X-ray tube showing a high activity and reliability, and having a relatively small weight. Other advantages will appear from the next part of the description.

The X-ray tube according to the invention has 35 an outer wall consisting of a metallic part which is insulated from the electrodes by means of insulating parts. Said insulating parts are closely surrounded by a metal envelope, which is designed to be electrically connected to ground. The metal envelope may then be connected directly or indirectly to the metal outer wall. It 40 is possible to also enclose in the said metal envelope the part of the high tension cables that extends between the tube and the stand. The 45 anticathode is provided with a current supplying conductor which rapidly carries away the heat and is rounded at the end turned away from the anticathode. The metal envelope is also rounded 50 at the ends of the tube and adjacent the anticathode the rounded part of the envelope has cooling apertures.

The tube comprises two glass portions united 55 by a metal part. This metal connecting part preferably consists of ferro-chromium, this alloy

being non-porous and eminently suitable to be sealed to glass. Its composition should be such that the thermal coefficient of expansion is substantially identical with that of the glass. The anticathode is sealed to one of the two glass portions, the other portion carrying a metal vessel in which the cathode is enclosed. The metal connecting part is provided with a window for the passage of the X-rays. The metal part of the outer wall may, if necessary be surrounded 60 by a lead jacket. Apertures for the passage of the high tension cables are bored at suitable points in the insulating cylinders. Then the tube and the high tension cables are surrounded by a metal jacket leaving the window free so 65 that the entire apparatus has the appearance of one entirely made of metal.

The metal connecting part of the X-ray tube is connected to ground so that the total high tension drop occurring between the cathode and the anticathode is evenly distributed between the 70 anticathode and the connecting part, and between the latter and the cathode.

The accompanying drawing represents, by way of example, a sectional view of an X-ray tube to 75 which the invention has been applied.

Referring to the said drawing, 1 represents a cathode, 2 an anticathode, 3 a metal vessel in which the cathode is arranged, said metal vessel being sealed at 14 to a glass tube 7, 4 and 5 are current supplying wires of the cathode, 6 is the current supplying cable of the anticathode, 8 represents an insulating cylinder. In order that the breakdown voltage may be increased, the leading-in wire of the anticathode is provided with a rounded end portion 9, the leading-in wires of the cathode being thick for the same reason. This end portion is recessed at 18 so as to permit a satisfactory attachment of the cable 6. A metal envelope 10 is provided with cooling aperture 11. 80 The cables are provided with metal sleeves 12.

The X-ray tube proper comprises a central metal portion 13 to which are sealed at 16 the two glass portions 7—7 of the tube. The metal envelope 10 and the metallic central portion 13 are apertured to form a window 15 through which the X-rays may emerge, whereas the X-rays which do not pass through the window, so far as they are not already absorbed by the metal portion 13, are absorbed by a lead jacket 17 surrounding the metal portion 13. The lead jacket is also provided with an aperture for the passage of the useful rays. Since the grounded metal envelope 10 is electrically connected to the metal part of the wall through the lead jacket 17, the average elec- 85 90 95 100 105 110

trode potential is equal to ground potential; moreover, due to the wall construction, the electrodes may have nearly similar effective voltages in relation to ground. By these means a greater safety is obtained, together with a very practical arrangement, the dimensions of the device being greatly decreased, whilst the entire outer surface of the tube may be touched without any danger.

The current supplying conductor of the anti-cathode is made of material that rapidly conducts away the heat so that this conductor also serves as a cooler of the anticathode. Cooling apertures 11 in the spherical part of the metal envelope serve to cool the said conductor. The distance between 10 the rounded part of the current supplying conductor of the anticathode and the rounded part of the metal envelope should be so great that at the operation tension no breakdown can ensue. In order that the breakdown voltage may be increased, the end of the leading-in wire of the 15 anticathode is rounded, the leading-in wires of the cathode being thick for the same reason.

What I claim is:

1. An X-ray tube having electrodes and a wall 20 comprising a metallic part which is insulated from said electrodes by means of insulating parts, the tube being closely surrounded by a metal envelope which is designed to be connected to ground and is rounded opposite the ends of the tube, the 25 rounded part of said metal envelope adjacent the anticathode having substantially the same center of curvature as the adjacent rounded end of the anticathode and being provided with cooling apertures.

2. A unitary structure comprising an X-ray tube 30 having a wall, portions of which are of metal and glass and a closely surrounding metal envelope spaced from said glass wall portions by insulating parts, said glass wall portions also insulating the metallic part of the tube wall from the tube electrodes, said metal envelope being 35 electrically connected to the metallic part of the tube wall and designed to be connected to ground.

3. A unitary structure comprising an X-ray tube 40 having electrodes and a wall comprising a metallic part which is insulated from said electrodes by means of insulating parts, and a metallic envelope completely surrounding the insulating parts and secured to the metallic part of the tube wall and together with the X-ray tube forming 45 an integral part of the unitary structure.

4. A unitary structure comprising an X-ray tube 50 having electrodes and a wall, portions of which wall are of metal and glass, and a surrounding metal envelope spaced from said glass wall portions by insulating partitions, said metal envelope being in electric connection with the metallic part of the tube wall and together with the X-ray tube forming 55 an integral part of the unitary structure.

5. A space-discharge tube having a wall comprising insulating portions and a metallic part, and a metal envelope surrounding said insulating wall portions throughout their entire length 60 and secured to the metallic part of the tube wall.

6. A unitary structure comprising an X-ray tube, the said tube having a wall formed of a substantially central metal portion and cooperating end portions of insulating material, electrodes 65 for the said tube separated from the metal portion by the insulating portions of the tube, a surrounding metal envelope forming together with the X-ray tube an integral part of the unitary structure, insulating partitions spacing the envelope from the said insulating portions of the 70

tube, and a lead jacket disposed between said partitions and in intimate contact with said envelope.

7. A unitary structure comprising a substantially cylindrical X-ray tube having a wall formed of metal and glass, and a surrounding metal envelope having a portion flaring outwardly in direction away from the metal portion of the tube, said envelope at its substantially smallest diameter being connected to said metal portion of the tube.

8. A unitary structure comprising a substantially cylindrical X-ray tube having a wall formed of metal and glass, and a surrounding metal envelope having two substantially frustoconical portions each increasing in diameter in opposite directions away from the metal portion of the tube, said envelope along its substantially smallest diameter being fixedly connected to said metal portion of the tube wall and peripherally thereof.

9. An X-ray tube having electrodes and a wall comprising a metallic part which is insulated from said electrodes by means of insulating parts, the latter being surrounded throughout their entire extent by a metal envelope connected to the metal part of the wall and designed to be connected to ground.

10. An X-ray tube having electrodes and a wall comprising a metallic part which is insulated from said electrodes by means of insulating parts, and a metal envelope designed to be connected to ground surrounding the insulating parts and connected to the metallic part of the wall, the anticathode being provided with a current supplying conductor which rapidly conducts away the heat and is rounded at the end turned away from the anti-cathode.

11. An X-ray tube having electrodes and a wall comprising a metallic part which is insulated from said electrodes by means of insulating parts, high tension cables leading to said electrodes and metallic sleeves surrounding said cables, a metal envelope surrounding the insulating parts of the tube and having apertured portions to receive said cables, said envelope comprising a waist section which surrounds and electrically contacts the metallic part of the tube, and supports in each lateral direction.

12. A unitary structure consisting of an X-ray tube comprising electrodes, insulating portions and a ray chamber defined by a metallic cylinder, said electrodes being electrically separated from the said metallic cylinder by said insulating portions of the tube, a metal envelope designed to be electrically connected to the ground completely surrounding each of the said insulating wall portions and a sleeve formed of X-ray opaque metal, the said metallic cylinder being surrounded by and electrically connected with said sleeve.

13. An X-ray tube having an evacuated container of substantial cylindrical shape, electrodes mounted therein and disposed in spaced relationship to form a discharge gap in the central portion of the tube, an X-ray opaque shield applied to the wall of the container and extending over said discharge gap and over the active portions of the electrodes, and a metal envelope closely surrounding said opaque shield and extending at both sides thereof over the container so as to completely surround same, the portions of the envelope extending beyond said opaque shield being in spaced relationship to the evacuated container, to form an insulating space between the envelope and container.

14. An X-ray tube having an evacuated container, electrodes mounted therein and longitudinally spaced apart to form a discharge gap, said container being formed with an equipotential waist section surrounding the discharge gap and the active portions of the electrodes, and a metal envelope substantially completely surrounding the evacuated container and showing a reduced middle portion which surrounds said equipotential waist section of the container and is secured and electrically connected thereto, said middle portion having an aperture and said waist section having a ray-pervious window in alignment with said aperture. 80
15. An X-ray tube having electrodes comprising a cathode and an anti-cathode and a wall comprising a metallic portion which is insulated from the electrodes by means of insulating wall portions and a metal envelope surrounding the insulating wall portions of the tube and supporting the tube in the middle portion thereof and designed to be connected to ground, said envelope being rounded opposite the ends of the tube and forming chambers around said ends, the anti-cathode chambers being provided with ventilating aperture, said anti-cathode having connected to it a heat absorbing body which is rounded at its end. 91
16. An X-ray tube having electrodes and a wall comprising a metallic part which is insulated from said electrodes by means of insulating parts, and a metal envelope designed to be connected to ground, surrounding the insulating parts and connected to the metallic part of the wall, and which envelope is rounded at the ends of the tube, the rounded part of said metal envelope adjacent the anticathode being provided with cooling apertures. 95
17. An X-ray tube having electrodes and a wall comprising a metallic part which is insulated from said electrodes by means of insulating wall portions, high tension cables leading to said electrodes and having metal sleeves surrounding same, and a metal envelope designed to be electrically connected to ground, surrounding the insulating wall portions and having an integrally formed cylindrical middle portion supporting the metallic part of the tube, and having apertured portions on each side of said cylindrical portion to receive said cables, said cable sleeves being electrically connected to said metal envelope. 105
18. An X-ray tube having electrodes and a wall comprising a metallic part which is insulated from the electrodes by means of insulating wall portions of the tube in spaced relationship thereto, said envelope comprising a cylindrical middle portion surrounding and electrically contacting the metallic part of the tube and supports the same in each lateral direction, said envelope being designed to be connected to ground and being rounded opposite the ends of the tube. 106
19. A unitary structure comprising an X-ray tube having a wall, a central portion of which is of metal and portions of which are of glass, and electrodes insulated from the metal portion of the tube wall by the glass portions thereof, a surrounding metal envelope designed to be electrically connected to ground and together with the X-ray tube forming an integral part of the unitary structure, insulating partitions spacing said metal envelope from said glass wall portions of the tube, said envelope being reduced in its section surrounding the metal portion of the tube, said metal portion being connected to said metal envelope at the reduced section. 110
20. A unitary structure comprising a substantially cylindrical X-ray tube having electrodes and a wall formed of insulating parts and a metal portion, the latter being insulated from said electrodes by means of the insulating parts and forming the ray generating chamber of the tube, 105 and a surrounding metal envelope having two substantially frusto-conical portions increasing in diameter in opposite directions axially away from the metal portion of the tube, a metal sleeve surrounding said metal portion and intermediate 110 to said metal portion and said envelope; the said metal portion, the said sleeve, and the said envelope being in electrical connection with each other and adapted to be connected to ground. 115
21. A unitary structure comprising a substantially cylindrical X-ray tube having insulating portions and an X-ray generating chamber defined by a metal cylinder, and a surrounding metal envelope designed to be connected to the ground and having a portion flaring outwardly 120 in the direction away from the metal cylinder, said envelope along its substantially smallest diameter portion being connected to said metal cylinder, and being apertured at its said smallest diameter portion, said metal cylinder having 125 a ray-pervious window in alignment with said aperture. 125
